UNITED STATES PATENT OFFICE.

PATRICK CAROLAN, OF CLEVELAND, OHIO.

INSULATING DEVICE FOR ELECTRIC CABLES.

1,011,118.

Specification of Letters Patent.

Patented Dec. 5, 1911.

Application filed December 9, 1910. Serial No. 596,442.

To all whom it may concern:

Be it known that I, PATRICK CAROLAN, a citizen of the United States, residing at Cleveland, in the county of Cuyahoga and State of Ohio, have invented certain new and useful Improvements in Insulating Devices for Electric Cables, of which the following is a specification.

This invention relates to splicing devices for electric cables, and the like, and has for its object, to provide means for insulating each section of the armor of the cable from all other sections, thereby protecting the whole cable from the destructive action of lightning and electrolysis; to lessen the danger of handling live cables both on poles and in subways; to protect all buildings connected with telephone, telegraph, or fire-alarm systems through such cables from fire due to live armor; to provide for better insulation for the splices and to reduce trouble in the splices; and to provide means for locating trouble in the cable without opening the splices, which is expensive and laborious.

This invention is embodied in a sleeve of suitable insulating material which surrounds the splice, and which has fusible end portions for uniting the said sleeve over the ends of the adjacent sections of the cable after the connection of the conducting wires has been made. Provision is also made for the filling of the said sleeve with insulating material to add to the efficiency of the device, and means are also provided for running test wires from the conducting wires to a position below the surface of the sleeve, which ends can readily be exposed for making tests, and for other purposes.

Other particulars as to the construction and arrangement of the invention, will be described hereinafter, and which are shown in the accompanying drawing of the invention, in which—

Figure 1 is a perspective of the insulating sleeve. Fig. 2 is a longitudinal section of the said sleeve, showing means for securing the fusible ends thereto. Fig. 3 is a section of the sleeve complete with the fusible ends. Fig. 4 is a longitudinal section of the device, after the splice has been made.

In the accompanying drawings, similar reference characters indicate similar parts throughout the several views.

The main sleeve of the device is shown at 5, and the fusible ends or cuffs are shown at 7. The said sleeve 5 is made of any

suitable insulating material, such as glass, fiber, clay, or the like, preferably clay, and can be made of suitable design. As shown, the said sleeve 5 has end collars 16 and a central collar 17, and also longitudinal ribs 18. This construction forms a strong sleeve with comparative saving in material and weight. The passage through the sleeve is indicated at 6, of which the central portion is swelled or enlarged as shown at 6'. At the ends of the sleeve 5 and on the inner side thereof are annular recesses 9, which are preferably corrugated, transversely thereof, forming lips 8 at the ends of the said sleeve which are spaced within the extended inner surface of the main body of the sleeve. The diameter of the opening between the lips 8 is larger than the diameter of the passage 6, for the purpose hereinafter described.

The fusible ends or cuffs 7 are secured to the sleeve 5 in the following manner:—A plug 15 is inserted into the end of the sleeve against the inside of passage 6, and a sleeve 14 is set on the end of the sleeve 5 over the projecting end of the said plug. Then lead, or other suitable metal or alloy, is poured into the space formed by the sleeve 14 and plug 15, while in a molten state, to form the said cuff on the end of the sleeve. This cuff 7 is secured hermetically to the said sleeve 5 by bead 10 engaging in the recess 9 and shoulder 11 bearing against the end of the sleeve 5. The plug 15 and sleeve 14 may be of any suitable design, but it is preferred to have them taper outwardly and inwardly, respectively, to provide for their easy removal when the cuff 7 is molded, and to also form the cuff 7 with a thinner outer portion. The corrugations in the recess 9 prevent the said cuffs from turning therein, which is preferable. It will also be noted that the cuffs 7 lie between the extensions of the planes of the outer and inner sides or faces of the sleeve, for convenience in use. The sleeve 5 also has several recesses 12 on the outer face thereof, preferably along one of the ribs 18, and a hole 13 passes from the bottom of each recess 12 through the sleeve 5 to the inner side thereof.

The device is used as follows: The sleeve 5 having the attached ends 7 is slid over the end of one of the sections of cable to be spliced. The metallic armors of the two sections of cable are shown at 19 and 19^a, and inclose, respectively, the wires 20 and

20^a, which are connected in the usual way. As shown, the ends thereof are wound together, after the insulating is scraped off the ends thereof. Test wires 21 are then 5 connected to the said connected wires, and the joint is then insulated by wrapping with tape 22, or any other manner. The free ends of the test wires are run out the respective holes 13 in the sleeve 5. The sleeve 5 is then 10 slid over the splice just made, with the ends 7 extending over the ends of the two armors 19 and 19', and the said ends are then soldered or fastened to the said armors by 15 fusion and by beating them inwardly against the said armors. This is frequently called a plumber's joint and is commonly used. In pounding the ends of cuffs 7 inwardly it will appear that the thickness thereof will increase. After this has been done ozite or 20 other insulating material is poured into the sleeve 5 through one of the holes 13 to fill the interior thereof. The swell 6' allows for the enlargement in the splice due to connection means, etc., and also tends to hold 25 the ozite or other material 27 in place. Bushings 26 are then slipped over the protruding ends of the test wires 21 and are pushed into the holes 13, and the free ends of the wires are scraped and flattened out on top 30 thereof. Bushings 26 are of suitable insulating material. Over the said exposed ends of the wires 21 are placed insulating buttons 25, cement 24, and an outer button 23, which is preferably of the same material as 35 the sleeve 5. This insulates the said test wires securely below the surface of the sleeve 5. The joint is then complete and it will be seen that the objects aimed at have been attained in an efficient and convenient manner. The various sections of the cable can 40

in this manner be insulated from one another, to prevent electric circuits therein, which are dangerous. The splice is also suitably insulated. And tests of the wires in the cables can be made by removing the 45 parts 23, 24, and 25 to expose the test wires 21, which are connected to the various wires in the cable. These test wires and holes 13 can be dispensed with if preferable, and this device can be used for splices in various 50 cables, such as electric light lines, telephone lines, and telegraph lines. After testing the wires 21 can be covered up as before.

Various alterations and additions can be made to this device within the scope of the 55 appended claims, and no limitations are inferred by the specific construction shown and described.

Having described my invention, what I claim as new is:

1. The combination with a sleeve having an interior annular recess and an end lip formed thereby, of a fusible cuff projecting beyond the end of said sleeve and provided with a locking bead and recess complementary to said recess and lip. 60

2. The combination with a sleeve having an interior annular recess and an end lip formed thereby, and said recess being corrugated, of a fusible cuff projecting beyond 70 the end of said sleeve and provided with a locking bead and recess complementary to said recess and lip.

In testimony whereof I affix my signature in presence of two witnesses.

PATRICK CAROLAN.
